A. F. JENKINS

COMBINATION CUTTING AND WELDING TORCH

Filed Aug. 11, 1919

UNITED STATES PATENT OFFICE.

ALEXANDER F. JENKINS, OF BALTIMORE, MARYLAND.

COMBINATION CUTTING AND WELDING TORCH.

Application filed August 11, 1919. Serial No. 316,640.

To all whom it may concern:

Be it known that I, ALEXANDER F. JENKINS, a citizen of the United States, and resident of Baltimore, State of Maryland, have invented certain new and useful Improvements in Combination Cutting and Welding Torches, of which the following is a specification.

It is the object of this invention to improve the construction of oxy-acetylene torches for welding and cutting metals, by the provision of a new and improved quick releasable gas valve controlling the supply of cutting oxygen to the tip and by the provision of an improved joint between the head of the torch and the removable tip.

The precise nature of the invention will be fully disclosed in the following description when taken in connection with the accompanying drawings in which:

Figure 1 is a side elevation of a torch, part of the handle being broken away to show the cutting jet valve;

Figure 2 is a disassembled view of the head and tip, the tip being shown in section;

Figure 3 is a section along the line 3—3 of Figure 1; and

Figure 4 is a section through the valve controlling the flow of gas to the cutting jet showing the valve in its open position.

The torch is, in general, of the usual construction in which three pipes 10, 11 and 12 for cutting oxygen, oxygen for the heating jet, and the acetylene gas respectively, connect the head 13 to the rear block 14. A tubular handle 15 surrounds and is supported by these pipes and the block 14. The valves 16 and 17 control the flow of oxygen and acetylene respectively from storage tanks to the torch in the well known manner, and a self-closing valve is located at a convenient point along the pipe 10 conveying the cutting oxygen to the tip. This self-closing valve comprises a valve casing 18 containing a cylindrical valve 19 normally pressed upwardly to its closed position by a spring 20. A valve stem 21 secured to the valve projects outwardly through the casing 18. By pressing upon the end of stem 21 the valve 19 may be opened against the pressure of the spring 20 and when the exterior pressure is removed the spring 20 automatically returns the valve 19 to its seat, thus interrupting the flow of cutting jet oxygen through the pipe 10.

Pivotedly connected at 22 to the valve

casing 18 is a lever 23 which extends rearwardly directly over the valve stem 21, and is adapted to operate the stem when moved by pressure of the finger. Slidably connected to the free end of the lever 23 is a button 24 having a catch 25. The button is adapted to be moved back and forth through a limited distance along the lever 23 by the thumb or finger of the operator of the torch, thus engaging or disengaging the catch 25 with the handle 15 which is slotted to receive the lever 23, and the end wall 26 of the slot serving as a stop for the latch 25.

In Figure 1 the lever 23 is shown raised, the valve 19 closed, and the supply of oxygen to the cutting jet cut off. In Figure 4 the lever 23 is shown depressed and the valve 19 open, so that cutting oxygen is passing to the tip. The latch 25 is shown caught under the stop 26 to hold the valve in this position in which it will remain until the operator slides the button 24 forward along the lever to disengage the members 25 and 26. By this arrangement of parts it will be seen that the oxygen supplied to the cutting jet is controlled by a quick release valve operating mechanism by means of which the valve may be opened and permitted to remain open for any desired length of time but which may be instantly closed by a simple movement of the thumb or finger of the operator when it is desired to cut off the supply of cutting oxygen.

An opening 15^a in the handle 15 is aligned with the removable cap 27 of the valve in order that the working parts of the valve may be removed. This is an advantageous feature, as these valves are subjected to considerable wear in the operation of the device and the replacement of parts is not infrequently necessary.

At their forward ends the pipes 10, 11 and 12 connect respectively with conduits through the head 13 which have their forward ends at various points in the conical seating surface 28 of the head. This conical seating surface 28 cooperates with an internal conical seating surface 29 of the socketed tip and, when the head and tip are securely held together by means of the coupling nut 30, a gas-tight joint is made between the head and tip. Annular grooves 31 and 32 in the head register with annular grooves 33 and 34 in the tip, and the annular passages thus formed when the head and tip are together, communicate with one or more

longitudinal passages 35 in the tip. The oxygen and the acetylene from pipes 11 and 12 respectively are led into the annular passages formed by the registering grooves 5 31, 32, 33 and 34. One of these annular passages communicates directly with the passage 35, and the other by a branch passage 35^a and the mixing of the two gases to form the heating mixture takes place in 10 the lower part of the passage 35 of the tip. The cutting oxygen passes through a central conduit 36 of the tip which communicates with the central conduit passage through the head and connected to pipe 10. 15 The use of tapered conical surfaces having registering annular grooves, as above described, has heretofore been suggested, but in said cases the head has been socketed instead of the tip. The present construction 20 has several important advantages over these previous constructions. A number of tips are usually provided with each torch and in changing them the extra tips are often not protected but are roughly handled and the 25 seating surfaces injured if exposed. By providing the tips with internal conical seating surfaces this trouble is obviated. It has been found that in use there is much less danger of the seating surface of the head 30 becoming bruised than of the tips.

The tip is also free to expand and contract as the torch heats and cools without breaking the sealing joint between the annular passages as sometimes happens when the 35 tip is provided with the external seating surface.

The torch described is simple, compact and conveniently operable, not easily injured by rough handling and is a thoroughly 40 practical structure in every respect. Various details of construction may, of course, be modified and I do not limit myself to the exact embodiment of the invention disclosed.

45 48 What is claimed is:

1. In a torch of the class described, con-

duits for gases including a conduit for cutting oxygen, a valve movable transversely of the handle for controlling the passage of fluid through said conduit, said valve having 50 a projecting stem, a spring normally tending to close the valve, a pivoted lever adapted to be forced against the valve stem to open the valve, a button slidably secured to the pivoted lever and provided with a 55 latch, said valve stem bearing against the lever at a point intermediate its pivotal axis and said button and a tubular handle surrounding the gas conduits and said valve, the handle being slotted for the pivoted 60 lever and the end wall of the slot serving as a catch for the latch secured to the button.

2. A torch having a hollow cylindrical handle portion provided with an opening in its wall, a gas conduit extending through 65 said handle, a valve casing in said handle having a removable cap, a valve in said casing for controlling the flow of gas through said conduit said valve being adapted to be withdrawn when the cap has been removed, 70 and the valve casing being positioned with the removable cap adjacent the opening in the handle, for the purpose set forth.

3. A torch having a hollow handle portion provided with a relatively small opening in its wall, a gas conduit within said handle for gases under pressure, means for controlling the flow of gas through said conduit comprising a valve casing with a gas 75 passage therethrough having an enlarged 80 portion constituting a valve chamber, a removable cap for said valve chamber positioned adjacent to and accessible through the opening in the handle, a valve in the valve chamber, and a valve stem connected 85 to the valve and extending through the valve casing, the valve and stem being removable from the casing through the opening in the handle when the cap has been detached.

In testimony whereof I affix my signature.
ALEXANDER F. JENKINS.
